CLAIM

The ornamental design for a ceiling light, as shown and described.

DESCRIPTION

1. Ceiling light

FIG. 1.1 is a perspective view of the design;

FIG. 1.2 is a front view thereof;

FIG. 1.3 is a rear view thereof;

FIG. 1.4 is a left view thereof;

FIG. 1.5 is a right view thereof;

FIG. 1.6 is a top view thereof;

FIG. 1.7 is a bottom view thereof.

The design is a ceiling light consisting of a first cylindrical body, a second cylindrical body and a third cylindrical body; the first body extends along a vertical axis, which is perpendicular to a horizontal plane; the second body extends along a first horizontal axis perpendicular to the vertical axis; the third body extends along a second horizontal axis perpendicular to the vertical axis and to the first horizontal axis; the second body and the third body are joined to the first body in the same zone; each cylindrical wall has an opaque portion and a translucent portion; the opaque portions of the second body and of the third are joined to the opaque portion of the first body; each body houses a LED light source;

The break lines in the drawings indicate that the appearance of any portion of the ceiling light between the break lines forms no part of the claimed design.
